UNITED STATES PATENT OFFICE.

ALONZO C. ARNOLD AND WILLIAM THOMPSON, OF NORWALK, CONNECTICUT; SAID ARNOLD ASSIGNOR TO SAID THOMPSON.

MACHINE FOR CURLING HAT-BRIMS.

SPECIFICATION forming part of Letters Patent No. 326,935, dated September 29, 1885.

Application filed December 27, 1884. (No model.)

To all whom it may concern:

Be it known that we, ALONZO C. ARNOLD and WILLIAM THOMPSON, of Norwalk, in the county of Fairfield and State of Connecticut, have invented certain new and useful Improvements in Machines for Curling Hat-Brims, of which the following is a specification.

Our invention relates to a machine for curling hat-brims, as hereinafter more fully set forth.

In the accompanying drawings, Figure 1 is an elevation of a machine adapted to carry out our invention; Fig. 2, a perspective view of the dies employed, showing them assembled as in completing their operation on the brim; Fig. 3, a perspective view showing the dies separated; Figs. 4 and 5, views illustrating the mode of applying and using the dies.

Prior to this invention attempts have been made to accomplish at one and the same operation the curling and shaping of hat-brims; but so far as we are informed such efforts have not met with success in actual operation.

Our apparatus consists of a bed or table, A, of convenient height for a workman, on which is mounted the bed-die B, of the form shown in Fig. 3. The die may be either stationary or swiveled, to permit it to be turned around in a horizontal plane for convenience in applying the hat-body and pressing the brim lightly into the die with the fingers, as is commonly done.

a b represent two sections of a die, C, which is divided to facilitate its application and removal. This die is of a form corresponding to that of the brim to be made, as is also the die B.

The hat-body comes to die B in a heated and softened condition, with the brim portion projecting horizontally all around, and a wooden block, D, in the crown portion, as indicated in Figs. 4 and 5. It is placed upon die B, as indicated in said figures. The brim is then gently or lightly pressed into die B, and then the parts *a b* of die C are placed upon said brim portion and pressed down so that the brim is caused to lie close upon the bed-die all around. The parts *a b* of die C are kept in place by a ring, E, which encircles the block D and the hat-body thereon, and fits within the inner opening of said die C, as

shown in Figs. 4 and 5. When the die C is thus placed upon the rim, the latter assumes, approximately, the shape of the space between dies B and C, receiving thereby both the longitudinal curvature or end dip and the lateral curvature required, the edges standing up all around, as at *c* in Fig. 4. At this point a hatter's iron is passed around over the upright edge, turning it down upon the die C, as at *d*, Figs. 4 and 5, the edge being moistened, heated, or steamed, if necessary, to make it sufficiently pliable. When the edge is thus turned in upon die C, a top plate or die, F, having an open center to pass over the hat-body, and of a size and form to fit the upper face of die C, is placed upon the rim, as in Figs. 2 and 5, and suitable force is applied to press the several dies firmly together, thereby giving the brim the exact form required, pressing or drawing out all wrinkles and uneven places, and giving the brim and its curled edge a permanent set.

If desired, the bed-die B or the top die, F, or both, may be made hollow and heated by steam or otherwise to keep the hat in a soft condition; but this is not essential.

For convenience in operation, the top plate or die, F, is secured to a cross-head, G, carried by upright standards H, connected with a counterbalanced treadle, I, the depression of which causes the cross-head to descend, as will be readily understood upon referring to Fig. 1.

After the brim has set properly, the cross-head is raised, thereby removing top die or plate, F, after which ring E is lifted out, and then the parts *a b* of die C, the division of the latter permitting said parts to be slipped out or withdrawn from beneath the curled edge of the brim without breaking, bending, or otherwise injuring the same.

The dies may be made of iron, spelter, or other suitable material.

The ironing and bending over of the edge after the body is applied to die B, and after the die C and ring E are applied, is a vital feature in our process, and it is this that insures the success of our plan. Being under perfect control of the operator and in plain view, this operation can be performed with the utmost accuracy and ease.

Having thus described our invention, what we claim is—

1. The herein described apparatus for bending and curling hat-brims, consisting of bed or table A, bed or die B, curved to the required form of the brim, two-part die C, ring D, top plate or ring, F, cross-head G, and treadle I, connected with the cross-head, substantially as shown and described.
- 5 2. In combination with die B, curved to the form of the required brim, two-part die C of a corresponding curvature, and ring E, adapt-

ed to enter the space between parts *a* *b* of said two-part die, and to maintain said parts in proper position.

- 15 3. In combination with bed-die B, two-part die C, and ring E, top die or plate, F, curved to correspond with dies B C, substantially as and for the purpose set forth.

ALONZO C. ARNOLD.
WILLIAM THOMPSON.
